WARMING PLATTER OR SIMILAR ARTICLE

Jerry E. Wright, Corning, N.Y.

Filed Aug. 1, 1962, Ser. No. 71,130

Term of patent 14 years

(Cl. D44—1)

Fig. 1

Fig. 2

Fig. 3

FIG. 1 is a top plan view of a warming platter or similar article embodying my new design.

FIG. 2 is a sectional view taken on line 2—2 of FIG. 1.

FIG. 3 is a bottom plan view of the same warming platter or similar article.

The broken line showing of the electric plug and cord in FIG. 3 is for illustrative purposes only, the cord being shown broken away for convenience of illustration.

I claim:

The ornamental design for a warming platter or similar article, as shown and described.
